UNITED STATES PATENT OFFICE.

ASA F. BATCHELDER, OF SCHENECTADY, NEW YORK, ASSIGNOR TO GENERAL ELECTRIC COMPANY, A CORPORATION OF NEW YORK.

ELECTRIC LOCOMOTIVE

No. 865,988.

Specification of Letters Patent.

Patented Sept. 17, 1907.

Application filed October 21, 1905. Serial No. 283,777.

To all whom it may concern:

Be it known that I, ASA F. BATCHELDER, a citizen of the United States, residing at Schenectady, county of Schenectady, State of New York, have invented certain new and useful Improvements in Electric Locomotives, of which the following is a specification.

In my Patent 808,717, dated Jan. 2, 1906, I have disclosed an electric locomotive in which the magnetic flux passes through the several armatures and pole-pieces of the propelling motors and thence through the mechanical frame of the locomotive. In practice the cross-sectional area of the mechanical frame of the locomotive is materially less than that required to efficiently carry the magnetic flux, and it therefore becomes necessary to either make the locomotive frame heavier than is necessary for mechanical purposes or in some other way to add sufficient metal to give the desired area at all points in the magnetic circuit.

The object of the present invention is to so construct and arrange the parts of an electric locomotive that the magnetic circuit may include all of the motor armatures and pole-pieces arranged in series, without necessitating the use of unusually heavy mechanical frames or other dead weight for the purpose of procuring the requisite cross-section in the magnetic circuit.

To the above ends I propose to arrange upon each of the driving axles two armatures, each of which has its separate pole-pieces, and connect the field coils in such a manner that the magnetic flux passes longitudinally of the locomotive through one set of armatures and pole-pieces and back again through the other set. In this way the only portions of the frame which need carry the whole flux are the cross members to which the pole-pieces at the extreme ends are attached.

In the accompanying drawing I have illustrated one form in which the present invention may be carried out, said drawing showing in plan view a locomotive frame with the driving wheels in place and motors mounted and arranged in accordance with the present invention.

Reference being had to the drawing, 1 and 2 represent the usual side members of a locomotive frame, and 3, 3, 3, cross pieces; 4, 4, 4, are sets of drivers associated with the frame in any usual manner. On each of the driving axles is arranged a pair of motor armatures, 5 and 6, rotating between poles 7, 7, and 8, 8, respectively. The armatures on each axle are illustrated as being connected to a common commutator 9 but it is of course understood that independent commutators 50 may be employed. The field winding or windings may be placed at any desired point or points and are of such character as to produce a magnetic flux of proper magnitude through one series of pole-pieces and armatures

and back again through the other series. A preferred way of arranging the field windings is to form each pole-piece of a core 10 supported upon one of the cross-members 3 and surrounded by a winding 11. By connecting the terminals of the several field windings properly to a source of current supply, the windings will generate lines of force which pass in the same direction 60 through one series of pole-pieces and armatures through a cross-member 3*, through the other series of pole-pieces and armatures and thence through the second cross-member 3*, which completes the circuit.

The principal frame members, 1, 2 and 3, it will be 65 seen, are not included in the main magnetic circuit and need not, therefore, be made heavier than is necessary to give the requisite mechanical strength. These members are not, however, entirely without function as magnetic elements of the motor apparatus, 70 since they provide local circuits for any excess of magnetism in the individual motors.

What I claim as new and desire to secure by Letters Patent of the United States, is,—

1. In an electric locomotive, two series of armatures and 75 pole-pieces arranged longitudinally of the locomotive, cross members at each end for completing a magnetic circuit through said series, and means for producing a magnetic flux through said magnetic circuit.

2. In an electric locomotive, a mechanical frame, two 80 longitudinally-extending series of pole-pieces supported upon said frame, armatures associated with said pole-pieces, and means for producing a magnetic flux through said two series of pole-pieces in series with each other and the associated armatures.

3. In an electric locomotive, a mechanical frame, driving axles mounted in said frame, a pair of armatures located upon each driving axle, independent pole-pieces for the armatures of each pair carried by said frame, and field windings for producing a magnetic flux through a circuit made up of one armature of each pair and its associated pole-pieces in series with the remaining armature of each pair and its pole-pieces. 85

4. In an electric locomotive, a mechanical frame, driving axles mounted in said frame, a pair of armatures located upon each driving axle, cross-members in said frame, independent pole-pieces for the armatures of each pair supported by said cross members, and field windings for producing a magnetic flux through one armature of each pair and its associated pole-pieces in series with the remaining armatures and pole-pieces. 95

5. In an electrical locomotive, a plurality of pairs of armatures arranged for rotation, and means for producing a magnetic flux through said armatures in series. 100

6. In an electrical locomotive, a plurality of shafts, two 105 armatures on each shaft, and field coils and cores for producing a magnetic flux through said armatures in series.

In witness whereof, I have hereunto set my hand this 20th day of October, 1905.

ASA F. BATCHELDER.
